DOUBLE MOSAIC SCREEN

Bernhard Bartels, Berlin, Germany, assignor to
 Telefunken Gesellschaft für Drahtlose Tele-
 graphie m. b. H., Berlin, Germany, a corpora-
 tion of Germany

Application January 9, 1937, Serial No. 119,723
 In Germany December 24, 1935

5 Claims. (Cl. 250—27.5)

The invention relates broadly to mosaic screens which are used in television transmitters, and more particularly to that type of mosaic screen which is commonly called the grid screen or the double mosaic.

Grid screens of the double mosaic type are in general comprised of a supporting metallic structure which is multi-apertured in form, that is to say, contains therein a considerable number of interstices. Through each one of these apertures or interstices there is passed a conducting element, and on the surface of the conducting element which faces the optical view to be transmitted, there is deposited a photoelectric light sensitive material. The other end of the conductor faces the cathode ray generating apparatus and is subject to bombardment thereby in order to neutralize the charges formed by photoelectric emission. It is clear, therefore, that all of these conductors in order to form discrete photoelectric units must be insulated from each other, and it is an object of this invention to provide a grid screen in which this is accomplished, and to provide a method of making such a screen in a practicable fashion.

The invention will best be understood by reference to the drawing in which

Fig. 1 shows a cross-section of the support member, and

Fig. 2 is a front view thereof.

Referring to the drawing in Fig. 1 10 represents the bridges of metal between the interstices or apertures; 11 represents the openings or apertures through which the conductors pass; and 12 represents the insulating layer which is provided for keeping the conducting elements electrically separate and discrete.

The method of forming the screen is as follows: the apertures 11 are filled with silver oxide in powder form or as a paste, the latter being obtainable by stirring the silver oxide in alcohol. The apertures having been filled, the silver oxide is heated to an appropriate temperature in order to reduce it to metallic silver, the temperature being in the neighborhood of 150° C. The oxygen thus liberated by the reducing process will oxidize the metal support, thus forming an insulating layer between the silver which now forms the conductor and the sieve-like support.

50 A photoelectric material may be deposited on the faces of the silver conductors which are placed on the side of the screen which is to be submitted to the photoelectric effect of an optical image.

The above described method has particular advantages if there is used for the support a metal

whose oxide is an electric insulator and if the insulating layer between the bridges 10 and the grid conductors is produced by oxidation of the surface of the bridges 10 before the silver oxide is reduced, are placed in the apertures. In this case defects in the insulating layer formed by the first oxidation will be eliminated by the oxygen liberated due to the reduction of the silver oxide.

Referring to Fig. 2, there is shown a front view of the support member to bring out the relative 10 positioning and shape of the support structure 10 and the apertures 11.

What I claim is:

1. In a double mosaic screen for cathode ray tubes in which a photosensitive material is deposited on one face of a number of discrete conductors passed through apertures in a metallic support, the method of assembling said screen which comprises the steps of oxidizing the surface of the apertures of the support so as to form 15 an insulating surface thereon, next filling the apertures with a metallic oxide, subsequently reducing the oxide, and finally depositing photosensitive material on one face of the metal obtained by the reduction.

2. The process of fabricating mosaic electrodes wherein conductors are passed through the interstices of a metallic support member which comprises the steps of placing in the interstices of the metallic support member a metallic oxide, reducing 20 said metallic oxide and simultaneously oxidizing the inner surface of said interstices with the nascent oxygen liberated by said reduction, and photo-sensitizing one face of the reduced metallic oxide.

3. The process of fabricating mosaic electrodes wherein conductors are passed through the interstices of a metallic support member which comprises the steps of placing in the interstices of the metallic support member a metallic 25 oxide, reducing said metallic oxide and simultaneously oxidizing the inner surface of said interstices with the nascent oxygen liberated by said reduction, and depositing a layer of photo-sensitive material on one face of each of the metal conductors formed by the reduction.

4. The process of fabricating mosaic electrodes wherein conductors are passed through the interstices of a metallic support member which comprises the steps of placing in the interstices of the metallic support member a silver oxide, reducing 30 said silver oxide and simultaneously oxidizing the inner surface of said interstices with the nascent oxygen liberated by said reduction.

reduction, and photo-sensitizing one face of the reduced metallic oxide.

5. The process of fabricating mosaic electrodes wherein conductors are passed through the interstices of a metallic support member which comprises the steps of placing in the interstices of the metallic support member a silver oxide, reduc-

ing said silver oxide and simultaneously oxidizing the inner surface of said interstices with the nascent oxygen liberated by said reduction, and depositing a layer of photosensitive material on one face of each of the metal conductors formed 5 by the reduction.

BERNHARD BARTELS.
